DESIGN FOR A TOWEL

Saul B. Fertig, New York, N. Y.

Application June 22, 1934, Serial No. 52,284

Term of patent 3½ years

To all whom it may concern:

Be it known that I, SAUL B. FERTIG, a citizen of the United States, residing at New York, county and State of New York, have invented a new, original, and ornamental Design for a Towel, of which the following is a specification, reference being had to the accompanying drawing, forming part thereof, and in which the figure represents, in plan, a quarter section of a towel, the section being repeated in the other three corners in proper relation to complete the towel.

I claim:

The ornamental design for a towel, as shown and described.

SAUL B. FERTIG.
